A. H. Ste Marie

· ATTORNEY

UNITED STATES PATENT OFFICE.

ALFRED J. SCHWARTZ, OF DETROIT, MICHIGAN.

OPERATING LEVER FOR ACCELERATORS.

Application filed March 1, 1923. Serial No. 622,046.

To all whom it may concern:

Be it known that I, ALFRED J. SCHWARTZ, a citizen of the United States, and a resident of the city of Detroit, in the county of Wayne and State of Michigan, have invented a new and useful Operating Lever for Accelerators, of which the following is a specification, reference being had therein to the accompanying drawing.

10 The present invention has reference, generally, to means adapted for regulating the velocity of prime movers or power-transmitting machinery, and it more especially relates to devices capable of varying the supply of gas or vapor to, and thereby controlling the speed of, internal combustion engines, such, for instance, as are now extensively employed for running automobiles or motor-vehicles.

20 The object of the invention is, first, to provide an improved device of the nature set forth which shall be most efficient for the purpose contemplated, both by furnishing always an adequate amount of motive power or energy to the engine for any desired rate of speed within established limits, and by grading the supply thereof in every case to meet the actual requirement, with proper regard for needed expenditure and heedful conservation.

Secondly, the invention aims at providing a reliable device of the character described, that can be depended on to act promptly, and in fact instantaneously, in delivering, checking, or withholding the amount of energy which it is able to supply, so that the engine fitted therewith may be speeded up, restrained, or slowed down to suit different times, localities, and conditions.

Another object is to produce a device of the class mentioned, so constructed and mounted for operation that it will admit of receiving and imparting firm, steady, and progressive impulses, in such manner as to preclude undue vibration of the engine which it supplies with gas or vapor, thus insuring the smooth-running thereof, and of the motor-vehicle as well, with all the material advantages thereby obtained.

A further object in producing a device of the type specified is so to design the same as to render it available for both old and new motor-vehicles, and to make it of such simple construction and easy application that it can be manufactured and set in op-

erative position by any mechanic of average intellect, provided with plain tools and common material.

Other objects and advantages of the invention will in part be obvious and in part be more fully brought out in the detailed description thereof hereinafter contained.

The invention consists of the novel improvements, parts, combinations, and features of construction herein shown and described, and pointed out in the subjoined claims.

In the accompanying drawing, which illustrates the invention in its preferred embodiment, and wherein similar elements are designated by corresponding reference characters wherever they occur:

Figure 1 is a top plan view of a practical form of the invention, applicable to any make or style of vehicle equipped with an internal combustion engine;

Fig. 2 is a vertical longitudinal section of the same form of this improved device;

Fig. 3 is a top plan view, showing the device on a reduced scale, as applied to the bottom board of a motor-vehicle, at the forward end thereof;

Fig. 4 is a broken transverse section of the said bottom board, with part of the device thereto affixed; and

Fig. 5 is a similar section of the board, shown in connection with a modified form of the invention.

The improved device constituting the subject-matter hereof has been shown in the annexed drawing, and is intended for use as an appliance to be worked usually by the foot, as described hereinafter. However, it will be obvious to persons skilled in the art to which the invention appertains, upon becoming conversant with the details thereof, that the same could be fitted for manual operation, and also might be incorporated in several different constructions. The accompanying drawing, therefore, is produced merely as affording a suitable and practical exemplification of the invention.

Referring first to Figures 3 and 4, the numeral 11 indicates the bottom part of an automobile body, having an upwardly-inclined board 12, located in front, to which the customary dash 13 is attached. The board 12, pursuant to the present invention, as applied to a new motor-vehicle, is provided with an aperture 16, preferably elong-

gate and rectangular in outline. This aperture is situated in the vicinity of the pedals ordinarily employed to operate the clutch and brake pertaining to the actuating mechanism of the vehicle, and by preference also, it is made to run transversely of the latter and longitudinally of the board.

Bordering the aperture 16 aforesaid, is a metal plate 17, having a slot 18, cut there-through, of coextensive dimensions. The plate 17 is countersunk in the board 12, and secured thereto by screws 19 (Fig. 3) passing through holes 21 (Fig. 1). The slot 18 is conveniently produced by incising 15 the metal of the plate along a median longitudinal line; next cutting it on short parallel lines transverse thereto, as at 22 and 23; and then parting it so as to form opposite flanges 24 and 25, fitting over the 20 adjacent sides of the board's aperture. The flanges need not extend the full length of the latter at their lower edges, and therefore the extremities 26 of each may be beveled or cut obliquely downward, as 25 shown in Fig. 2, to remove unnecessary metal and improve the appearance.

Within the plate above described, is mounted a lever 29, designed for oscillation through the slot therein. This lever, 30 as clearly seen in Figs. 1 and 2, is longer than the said slot, and positioned diagonally with relation to the same, one of its ends extending under and the other end over the corresponding extremities of the 35 plate. The lower end of the lever is arranged to swing about a pivot or hinge-pin 31, secured transversely to the plate, within a three-sided inclosure formed by turning down a terminal portion of the latter, as at 40 32, and deflecting the corners 33 and 34 of the bent portion inwardly from opposite sides. At the upper end, the lever projects above the plate, beyond the adjoining extremity of the slot. Thus mounted, the lever 45 is permanently held under the plate at its pivoted end, and constantly kept above it at the free end.

Preferably, the lever 29 is made of rectangular shape, similar to that of the plate 50 and slot, and is smooth-surfaced throughout. It is further provided with lateral flanges 37 and 38, depending from its opposite longitudinal edges. The latter-named flanges 37, 38, coact with the 55 previously-mentioned flanges 24, 25, of the plate 17, in guiding the lever in its oscillatory movements in and lengthwise of the slot 18. The opposite extremities of the flanges 37, 38 are trimmed off on oblique 60 lines, as at 39, in conformity with the similar bevels 26, on the flanges 24, 25. Beyond its said flanges, the lever is turned up at one end to form a loop 41, encircling the pivot 31, and remains straight at the 65 other end, which runs above the slot in the

plate. Apart from the loop 41, the body or main portion of the lever is made flat and straight, in the form of the invention herein exemplified.

As will be readily perceived, the lever 29 70 is intended to replace the pedal, with mushroom head, commonly provided to operate accelerators. Like the pedal, it is operatively connected with the throttle valve that controls the supply of gas, vapor, or 75 motive force to the engine of the vehicle, but there the similarity ceases. In the form of the invention now under consideration, the connection between the lever and the valve simply consists of an intermediate 80 link or rod 44, the upper end of which is externally threaded and engages an internal thread formed in a head or socket-piece 45, suspended by a pivot 46, from the underside 85 of the lever, between its side flanges 37 and 38. The connection is with the central part 90 of the lever, as shown in Figs. 1 and 2, but it can as well be made either forward or to the rear thereof, as the flanges 37, 38 are provided at several points in their length 95 with aligned holes, as 47, through which the pivot 46 may be passed. The shifting of the connection, it is understood, would vary the purchase of the lever, and incidentally increase or decrease its range of oscillation. 100 The rod 44 is normally raised, and when released after being depressed to open the throttle valve, it is returned to its initial position, with the lever surmounting the same, through the action of a well-known 105 form of resilient mechanism, which it is not necessary here to describe or illustrate.

The operation of the device, as thus far described, is as follows: Having been applied to the automobile a little to the right 110 of the steering-wheel thereof, in the manner represented by full lines in Fig. 3, the lever 29 stands in a favorable position to be placed under the chauffeur's right foot, and to be operated thereby. It may be assumed, for the purposes of this specification, that the steering-wheel is located as at 51, in the view last named, with the clutch and brake pedals at 52 and 53, respectively, and the gear-shift lever standing up from the floor 11, of the automobile body, at 54, all as ordinarily constructed. The foot, being placed across the slotted plate 17, near the hinged or pivoted end of the lever, obtains at once a firm bearing thereon, and upon the contiguous portions of the upwardly inclined board 12, on both sides of the elongated aperture 16. From this point, the foot can be easily and gradually moved toward the right, transversely with relation to the said aperture and the corresponding slot 18 of the plate 17, thereby operating to depress the lever 29, and consequently to open the throttle valve more or less, depending on the extent 130

of the sliding movement of the foot in that direction. It is understood that in the meantime the foot should be kept in contact with the plate and the floor into which the latter is countersunk. Using the contact as a guide, the chauffeur will never fail to attain the desired result of opening the valve positively, uniformly, and without jar, concussion, or vibration of any sort.

10 As a consequence, the smooth running of the vehicle is assured, and the life thereof proportionately prolonged. The lever automatically rises to the position which it previously occupied, as soon as relieved

15 from the pressure of the operator's foot, owing to the nature of its connection with the throttle valve, hereinbefore mentioned.

Similar results would be obtained by cutting the aperture 16 across the board 12, instead of lengthwise thereof, and accordingly by placing the slotted plate 17 in the position indicated by dotted lines in Fig. 3. In such a case, the foot operating the lever would be moved up and down in the direction of the slot in the plate, and not to the right or left, as in the previous instance.

Fig. 5 illustrates a construction particularly adapted for used motor-vehicles, to which the present invention is to be applied. The board 12 is not cut into to provide therein an elongate aperture, in this modified construction, but there is placed upon it another board 57, affording a like aperture 58. The slotted plate 17 and other parts of the device, already described, are fitted to the latter-named board and aperture, obviously with identical results. The link or rod that connects the operating lever and throttle valve may be passed through any opening before provided in the bottom of the vehicle for a similar purpose; and in the absence thereof, it is a simple matter to bore a hole, as at 59, in the board 12, directly under the aperture 58, so as to effect the required connection.

While this improved device has been shown and described in its preferred forms, it will be understood that numerous changes may be made in the shape, size, proportion, and arrangement of the several parts there-

of, without departing from the scope of the invention as defined by the claims hereto appended.

What I claim, and desire to secure by Letters Patent of the United States, is:

55

1. A device of the character described including, in combination with a slotted plate fitted in an apertured member of a motor vehicle, a depressible lever diagonally mounted in the slot of said plate 60 lengthwise thereof, flanges on said lever guiding the same conjointly with the opposite sides of said slot, a self-rising link adapted to open the throttle valve of the vehicle's engine, and means flexibly connecting said link to said lever.

65

2. An operating lever for the accelerating mechanism of an automobile engine, including, in combination with an apertured board of the automobile's body, a plate having a slot coinciding with the aperture in said board, a depressible lever of greater length than said slot extending in a diagonal direction therethrough, lateral flanges on said lever guiding it by the sides 75 of the slot, a terminal portion of said plate inclosing thereunder the adjoining end of the lever, a hinge connection between the latter and said terminal portion, and automatically rising means serving to open the 80 throttle valve of the engine through depression of the lever by a sliding movement of the foot in contact with the slotted plate.

70

3. A device operable to open the throttle valve of a motor vehicle engine, including, 85 in combination with a foot board of the vehicle bored through to let pass a working member of said valve, another board superimposed upon said foot board having an elongate aperture entered by said member, a slotted plate fitted in said aperture, a lever exceeding in length the slot of said plate mounted diagonally therethrough, said lever being in position to be depressed by the foot sliding in contact with the 90 slotted plate, and means pivotally connecting the lever with the valve working member.
